United States Patent Office.

JAMES CALKINS, OF NEW YORK, N. Y.

Letters Patent No. 81,749, dated September 1, 1868.

IMPROVEMENT IN LAMPS.

The Schedule referred to in these Letters Patent and making part of the same.

TO ALL WHOM IT MAY CONCERN:

Be it known that I, JAMES CALKINS, of the city, county, and State of New York, have invented a new and useful Improvement in Lamps for burning petroleum and other hydrocarbon-fluids; and I do hereby declare that the following is a full and exact description thereof, reference being had to the accompanying drawing, it being a central vertical section of one of my improved lamps.

My invention consists in the construction of lamps with a divided reservoir for oil, the supply portion of which communicates, by means of a tube passing through a channel of water or other cooling-medium, with the wick-chamber, whereby the oil, which is in direct consumption by the burner, is kept at a lower temperature than the surrounding atmosphere, and also in providing the consumption-reservoir with an annular insulating-space, and also in providing for the escape of vapors from the consumption-chamber directly to the surrounding atmosphere at a safe distance from the burner through the insulating-space, all as hereinafter set forth.

The object of my improvement is to obviate the danger of explosions in hydrocarbon-oil lamps, by keeping that which is in the wick-chamber always cool, both by passing it through water and by intercepting the heat which the oil is liable to absorb from the heat of the burner and surrounding atmosphere, and also by allowing a free escape for the vapors.

As represented in the drawing, A is the main reservoir for oil; B is a chamber filled with water or other cooling-substance, most conveniently placed in the base of the lamp; C, a duct or coil, which conducts the oil from A through the water-chamber and into the consumption-chamber D. E is the wick, and F is the burner, which may be of any desirable kind.

The wick-chamber D is comparatively small, and occupies the centre of the large reservoir. It is provided with an intervening air-chamber, G, between the two. As the oil in A is liable to become warm from heat absorbed from the burner, the air-space G, being non-conducting, prevents the oil in D, which has been cooled by passing through the coil C, from being raised in temperature. The oil stands at the same level in both chambers, and there being only sufficient in D to keep the wick well supplied, the evaporation therefrom is slight, but I provide for the free escape of any vapor which may arise, by means of perforations *h h* placed near the top, but some distance below the flame.

Corresponding apertures *h'* are made in the outer wall, but covered with wire gauze *i i*, to prevent the vapor from igniting in the interior of the lamp should these openings be exposed to flame. By thus providing for keeping the portion of immediate supply cool, and allowing free escape of the volatile portions through the two walls enclosing the supply-chamber D, the possibility of explosions is obviated, and even oils of a dangerous gravity, or naphtha, may be burned in this lamp with safety. Explosions cannot occur from internal pressure, for any vapors which arise in the reservoir A find escape directly through the gauze openings *i i*, a space being left at *i*, between the wall of the lamp and the outer partition of G, for that purpose.

What I claim as my invention, and desire to secure by Letters Patent, is—

1. The divided chamber, consisting of the reservoir A and consumption-chamber D, in combination with the duct or coil C, and water-chamber B, arranged and operating substantially as and for the purposes set forth.

2. I also claim the intervening air-space G between the chambers A and D, as and for the purposes set forth.

In witness whereof, I have hereunto signed my name in the presence of two subscribing witnesses.

JAMES CALKINS.
